(57) **CLAIM**

The ornamental design for a display screen or portion thereof with graphical user interface, as shown and described.

DESCRIPTION

A portion of the disclosure of this patent document contains material which a claim for copyright is made. The copyright owner has no objection to the facsimile reproduction by anyone of the patent document or the patent disclosure, as it appears in the US Patent and Trademark Office patent file or records, but reserves all other copyrights whatsoever.

FIG. 1 is a front view of a display screen or portion thereof with graphical user interface showing the graphical user interface enlarged and separate for clarity of illustration; and, FIG. 2 is a front view of a display screen or portion thereof with graphical user interface.

Additionally, the Applicant notes that the diagonal broken lines in FIGS. 1-2 illustrate a contrast in appearance.

The outer broken line showing of the display screen or portion thereof and all other broken lines showing portions of the graphical user interface are included for the purpose of illustrating portions of the article and form no part of the claimed design.
